GOLF TEE

Ray Belmont Whitman, Essex Fells, N. J.

Application June 3, 1936, Serial No. 83,175

4 Claims. (Cl. 273—33)

This invention relates to golf tees, and more specially to the type of golf tee which rests on top of the ground and has an extended base for supporting the golf ball.

1. An object of the invention is to provide a golf tee which can be manufactured and sold for such a small sum that a golfer can easily afford to use one tee for each shot or drive and not bother to pick it up again.

10 Another object is to provide a tee so compact in size and shape that a sufficient number for a full round of eighteen holes of golf may be assembled in a space small enough to fit into the vest pocket, for instance, while yet being adapted to be instantly removed one at a time as needed.

15 Further objects are to provide a tee which can be made of cardboard or light easily-destroyed material, which will quickly disintegrate through action of the rain or other elements when left behind on the golf course, which can only be hit or blown a foot or two, and which, moreover, could not possibly injure the blades of a lawnmower if left in the grass to be cut.

20 Another object is to provide a golf tee which will move but a short distance no matter how hit by the player's club, nor how hard the wind blows, thus keeping the tees concentrated on the teeing-off place, for easy removal by the employees of the golf course, or for ready retrieving by the player if he is so "Scotch" he desires to use this cost-less tee again.

25 Yet a further object is to provide a golf tee originally in flat sheet form but which can be instantly folded, even with cold numb fingers, to a shape which will elevate the ball from the ground when same is mounted on the tee.

30 A further object is to provide a golf tee adapted to mount the ball at different pre-determined exact distances from the ground, at the will of the user.

35 A still further object is to provide an advertising book, the leaves of which may both contain an advertisement and be used as a golf tee, when suitably folded, or the cover of which may be so used for advertising, or both.

40 A still further object is to provide a golf tee and score card in combination, in which attached inner-folded sheets within the score card each have a plurality of tees which may be individually severed for use, the entire article being made from a single sheet of like material.

45 Another object is to provide a new method of teeing a golf ball to a plurality of pre-determined heights, by simply grasping a flat foldable

member at a like plurality of positions and folding same to each said desired height.

5 A further object is to provide a tee with a ball-receiving surface which makes only point contact with the ball, instead of line or surface contact, as in the ordinary peg tee, and thus aids in giving distance and direction to the ball by reducing the frictional engagement between ball and tee.

10 Another object is to provide a method of teeing a golf ball in which the step of introducing anything into the ground (as in the case of a peg tee or otherwise) is eliminated.

15 Another object is to provide a golf tee having no sharp projections which might injure the user, or tear holes in his or her clothing, said tee being of a character where a large number can be conveniently carried in one protective container.

20 Another object is to provide a method of forming attached paper golf tees and quickly separating one of them at a time from the rest, in which flat cardboard or other suitable foldable stock is punched or otherwise formed to the desired shape and score lines for folding also formed therein either in the same operation or otherwise, and which operations include one of almost wholly severing each tee from its companion attached tee or from an intermediate attaching means thereto.

25 Another object is to provide a method of teeing-up golf balls in which the teeing means is formed of flat material and carried thus to the tee place, and then pressed into elevating shape prior to use.

30 Another object is to provide a golf tee with an outwardly-sloping edge contact between the tee and the ground, to form a comparatively extended base, almost ball-diameter in extent, so that a very stable base on ground or turf is assured.

35 Another object is to provide a tee which can be used equally effectively in mid-summer, on hard sun-baked ground, or at other seasons when the ground is softer.

40 Another object is to provide a tee with a supporting base almost as large as the ball itself—for successful use even on rough ground—while yet concealing the tee beneath the ball to eliminate all mental hazard.

45 Yet another object is to provide a tee having a downwardly-outwardly slanted surface or surfaces, or other equally-effective means for camming the tee firmly to the ground to help it stay in place when the wind blows; also to cam the

club head up to the ball during a too low stroke.

Still other objects are to provide a tee which cannot injure lawn-mower blades; which will be self-destructible in use by being made of a cheap 5 cardboard or like material which will disappear in the first hard rain; which is grass-colored, so there will be no distraction to the golfer's shot concentration while in use, and no litter or unsightliness when left behind at the tee ground; 10 which cannot be blown or hit more than a foot or two, so is easy to either retrieve or collect discarded ones; which will eliminate the disadvantages of the wooden peg tee as the latter did the sand tee, and which—in fine—will be the 15 best tee at the least cost.

All these and other objects, as suggested herebelow, are attained by the article and method now to be described, and illustrated in the accompanying drawings, in which—

20 Fig. 1 is a side elevational view, partly in perspective, of an approved form of the invention showing the position of the golf ball mounted thereon, the tee being folded to make a low tee for the normal or long drive.

25 Fig. 2 is a similar view, showing the same tee folded to mount the ball high, used particularly for a drive up-hill or a short drive, or by certain golfers to better accommodate their strokes.

Fig. 3 is a plan view of one of the leaves in a 30 book of tees in one of its modified shapes, a quantity of which leaves are assembled between covers or otherwise to form the complete book of golf tees, although of course they may be used singly in bulk, in which case the flap at 35 one side would not be needed.

Fig. 4 is a similar view of one sheet of the book comprising one golf tee in one of its forms and showing the tee detached from the stub which holds it in the book until needed.

40 Fig. 5 is a perspective view of a partially-used book of tees of the form of Fig. 4.

Fig. 6 is a longitudinal cross-sectional view of the book shown in Fig. 5 before any of the leaves of the tees have been detached.

45 Fig. 7 shows a modified form of the golf tee book or pack of Figs. 5 and 6, but where the tees are separated into a plurality of portions—in this case, two—and held together within the cover of the book through a common centrally-disposed connecting tab portion.

50 Fig. 8 shows one of the duplex or double tee leaves from the book of tees shown in Fig. 7.

Fig. 9 shows the position of the golfer's fingers when ready to fold or form by pinching one of 55 the forms of tees of this invention along the side score lines to form a high tee.

Fig. 10 shows the position of the golfer's fingers for forming another slightly modified form of tee, but in this case along its scored diagonals to 60 form a low or standard height tee.

Fig. 11 shows an advertising folder or other printed object used as a cover or leaf and attached to a plurality of the golf tees of this invention, said tees being themselves attached in 65 multiple to each other along their edges in a plurality of horizontal and vertical rows.

Fig. 12 shows a perspective view of an ordinary two-fold score card, but in conjunction with a plurality of these golf tees, all made from the 70 same sheet of like material, and the several sheets of tees being attached to be folded in accordion-style within the folds of the score card.

Fig. 13 shows a modified form of the golf tee in 75 which the central opening is cut substantially in

the form of a square placed diagonally to the generally-square peripheral edge of the tee.

Fig. 14 is a view similar to Fig. 13 of one of the forms of individual tees comprising this invention, but in which the central opening which forms the base or rest for the ball is substantially octagonal in outline.

Fig. 15 shows a plurality of individual detached golf tees of this invention positioned in a permanent resilient holder or cover arranged so that their edges when inserted in said cover extend therefrom in a slightly staggered position as an aid in picking up one tee at a time. In this adaptation of the invention the holder has its front and back portions resiliently movable with respect to each other to clamp any number of tees between them, from 1 up to 18 or 20 for instance, to hold said tees in place until wanted and to provide a convenient and permanent carrying case for protecting and keeping them together, as well as for an ornamental or jewelry item.

Fig. 16 is a plan view, full size, of a successful form of the tee itself, showing its present preferred dimensions, and scoring, and

Fig. 17 is a perspective view of a plurality of individual tees nested and held together by the simple expedient of only partly severing the circle or center section of the tee which forms its opening, and assembling them with their attached tab portions so formed in alignment, and then pressing or bending the plurality of tags outwardly, for instance, so that the lowermost tab projects more or less upwardly through the center opening of the uppermost tee of the group, as clearly shown.

Like numerals refer to like parts throughout the several views.

This tee is formed from suitable foldable material, preferably thin inexpensive cardboard. The tee is completely manufactured from flat stock and remains flat until folded into tee form by the golfer, usually just prior to his drive. The complete manufacture of the tee consists merely in blanking out its shape, consisting usually of a generally-square outside perimeter with somewhat concave sides and beveled corners, and a centrally-disposed opening or hole about half as large as the tee itself and preferably of circular or octagonal outline, and scoring lines of fold on one or both surfaces of the tee as an aid to the golfer in later forming the flat blank into finished tee form for holding a golf ball in an elevated position above the ground.

In one of the preferred forms of the tee, shown for instance in Fig. 4, it is shown as made of a flat cardboard-like piece of material 20, slightly smaller than the ball, generally square in contour but having its four sides somewhat concaved or angled-in, in shape as shown at 21. 25 These generally concave-shaped sides extend to the corners of the tee, as shown, and said corners moreover are cut off at right angles to the diagonals 26 as shown at 22, to make a generally-blunt point to the tee at each of the four corners 30 when same is folded into tee form. A centrally-disposed opening 23, preferably circular or octagonal, but which may be square as shown, positioned in generally-parallel relation to the sides of the tee, is cut from the blank and is substantially from a third to a half as long on its sides as are the sides of the tee blank itself.

Where the tee is to form one leaf of a plural-leaf book of tees, such as that shown in Fig. 5, each tee blank also comprises a detachable tab 35

portion 24 largely cut from said tee blank during the process of forming same, and held thereto by spaced uncut portions which may be easily severed as at 25, 25 by a slight sideways pull or tear on the tee.

To facilitate the folding of the tee along its diagonals and side radii, scored lines 26 are formed along the four diagonals connecting the opposite corners of the tee and its opening, and other scored lines 27 are formed connecting the middle of the sides of the tee with those of the opening. These scored lines may all be formed from one side or both sides or if desired the diagonals may all be scored into the material from one side and all the side scorings from the other side.

In the simpler but less accurate form of tee shown in Fig. 3, the outer edges of the tee are not concaved, but have straight sides as shown, 20 being detachable, for instance, from adjoining sides not shown (as where a plurality of tees are formed in one sheet) by means of lines of perforation 28, one of these lines of perforation also serving to permit the tee to be severed from its tab 29. In this form of the invention the centrally-disposed opening is not square but is in the form of two squares imposed upon each other, one of the squares having its sides parallel to the sides of the tee and the other square having 30 its sides at 45 degrees thereto, forming an eight pointed star-shaped opening so that a similar pointed portion of the opening extends both from the diagonal scores and the side scores. This view shows the four diagonal scores marked "L" 35 (meaning "Low") and the four side scores "H" (meaning "High") as an aid to the golfer folding the tee for use. Thus, he would pinch or fold along the diagonals marked "L" to convex them when forming a low or standard tee, and would 40 likewise pinch folds along the scored lines marked "H" to convex them when forming a high tee. During these operations the adjacent series of scores are folded in the opposite direction—that is, the convexing along the scored diagonals at 45 the same time concaves along the side scores, and vise versa.

The tee when folded to a low or standard position is shown in perspective in Fig. 1 with the representation of a golf ball 43 mounted thereon. 50 And the perspective view of the tee shown in Fig. 2 is the same tee as in Fig 1, but where the folds are convex (looking down from the top) along the side scores 27 and concaved along the diagonal scores 26. Note that in this manner the ball may be elevated up to one-quarter inch more than with the low tee.

It will be seen that the tee formed in this manner provides a stable and sure base or support for the golf ball, whether folded for a low tee or a high tee, one in which the lower supporting portions of the tee which engage the ground are a series of spaced peripheral projections to provide a stable base even on comparatively rough ground; and also a plurality of upwardly-extending ball-holding portions is provided around the edges of the opening in such manner that the ball is effectively but very lightly mounted in point contact along the edge of the tee, regardless of whether it is folded for a low tee or 65 a high tee.

The perspective view shown in Fig. 5, and in longitudinal cross-section in Fig. 6, shows a book of these tees, for example in the form of Fig. 4, stapled together by means of a wire staple 30 75 between a front and back cover 31, 32, which

may be a single piece of folded material such as cardboard and put together either in book form or with a front-edge captive flap as is done in ordinary "papers" of matches. When the tees are assembled thus in book form they may be readily removed one at a time from either the front or the back of the book. And if attached in slightly staggered relation, one of them may be even more readily grasped, as by the staggered or "grasping" outer edge.

A modification of this tee, so far as its holding means is concerned, is shown in Figs. 7 and 8, in which a connecting flap 33, Fig. 8, serves to hold the two connected tees 20, 20 together along adjacent edges. In this form of tee, as shown in Fig. 8, the square centrally disposed opening 23 has been cut away along a perforated line 24 to provide a roughened edge to grip the surface of the ball. This feature, however, is not essential. The book of tees formed two to a sheet as in Fig. 8, is shown in perspective in Fig. 7, wherein the staples 34 serve to show how the plurality of double tee sheets are held together to a cover member 35 having its opposite ends folded and meeting in a central position on the upper surface of the book where one end may be tucked beneath another or otherwise suitably held together for convenience in carrying.

When forming the tee from the flat prepared blank into elevating position to support the ball 30 prior to driving, the simplest way to do it is to position the thumbs 36, 36 of the two hands, Fig. 10, (in case a low or standard height tee is desired) over the tee blank 20 and just below a pair of opposite diagonals 26, 26 (as viewed in the drawings) and the two index or first fingers 37, 37 along side of the two thumbs and just above them and also on the upper surface of the tee as shown in Fig. 10. The two second or longest fingers are positioned below the tee and along the 40 line of these two diagonals between the two fingers above. Note that the pair of thumbs and the pair of first fingers are so positioned respectively over the two lower side scores and the two upper side scores as to cover them; and now 45 by merely pressing the thumb and first finger of each hand together and also down on the second finger of said hands simultaneously, and at the same time bringing the ends of the fingers of the two hands toward each other laterally, the tee is 50 formed by convexly folding along the four diagonal scores 26 and concavely folding along the four side scores 27.

In order to form a high tee the tee blank 20 is merely grasped in a different position so that the thumbs 36, 36 and the first fingers 37, 37 and the second fingers 38, 38 are all in a line parallel, not to an opposite pair of diagonals as in Fig. 10, but instead, to opposite side scores as clearly shown in Fig. 9. In this case the side scores are all four folded convexly (looking down from above as in Fig. 9) and the four diagonals are folded concavely which is just the reverse of the previous action although the operation of folding is identical, except, as stated, the golfer grasps the tee in the first instance along two opposite corners and in the present instance midway of two opposite sides. The ends of the fingers mostly form the concave folds and their end longitudinal surfaces the convex folds.

Modifications in the shape of the centrally-disposed opening over those previously shown are illustrated in Figs. 9 and 10, and also in Fig. 9 the four corners of the tee blank are notched 75

as shown in lieu of being beveled, as in Fig. 4 for instance.

For use with an advertising folder a plurality of these tees readily detachable along 5 perforated lines, as shown, or otherwise, may be assembled in plural rows both vertical and horizontal along one edge of an advertising card 39, Fig. 11, for instance.

A particularly useful form of these tees may be 10 in connection with an ordinary folded score card 48, Fig. 12, to which there is detachably secured, for instance along the back edge thereof, three leaves of six or more tees each, as clearly shown in Fig. 12. These sheets are attached consecutively and in an accordion-pleated fashion and folded together with the score card, so that one tee at a time can be detached until all 18 have been used and the round of golf completed.

The square centrally-disposed opening shown 20 in tee blank 20 in Fig. 4 may be positioned diagonally of the tee sides, as shown in Fig. 13, or this opening may be circular in outline as shown in Fig. 16. In the former case the corners of the opening are in line with the side scores 27.

25 Fig. 15 shows a plurality of the tee blanks 20 held in a resilient clamping cover 42 having a base portion extending over the area of the tee and a top or clamp portion extending, as shown, perhaps partially over the top of the tees and so 30 arranged that the connecting side 42-a is on a slant and not at right angles to the surface of the bottom of the cover, so that the outer grasping edges of the tees will be staggered for aid in removing one tee at a time from the clamping 35 cover. This clamping cover may, of course, have advertising on its surface as, indeed, can also the surfaces of the individual tees in the various modifications suggested and their attached elements, such as book covers and score cards. Or 40 it may be a jewelry item, of gold, initialed, etc.

Experience has shown that one of the most 45 successful shapes for this article is that shown in Fig. 16, or modified by substituting an octagonal hole for the circular hole. The concaved sides of the perimeter of the article are made with two straight lines, as shown, in flat notch form instead of on a curve such as a circular arc. Also the depth of this notch at the center of the side must be just right, for if too small the base of 50 the tee will rock on the side-center edge surfaces, which engage the ground first and hold the corner portions slightly out of contact therewith; and if these side notches are too deep the corner portions will touch the ground first and leave 55 the side center portions slightly elevated, in which case the weight of the ball mounted on such a tee will tend to collapse it. Of course, the ground is usually somewhat rough so slight variations in the shape are not always serious; nevertheless it is best to have these notches so shaped as to 60 their center depth that when the tee is pinched into folded position and then released, and springs back part way to its permanent position, the side edges of the tee should preferably, or at least in some cases, make contact with the ground all along them.

The corners are beveled as shown in this figure largely to present a strong uncollapsible corner support for the tee when folded for a high tee, 70 and also to conceal wholly or partly said projecting corners beneath the ball when used as a low tee, while yet getting the advantage of having the edge support of the base of the tee on the ground as far out from the center as 75 possible and still be out of sight beneath the

ball. This design or shape of tee has also been very carefully developed with the consideration in mind of utilizing the least dimensioned blank possible, so as to save material.

As a means of holding a quantity of the tees 5 together in the simplest possible way, the portion of the blank which is normally removed to provide the center opening may be only partially severed from the blank, being held thereto at one point perhaps a sixteenth to an eighth of an 10 inch in width, as at 44, Fig. 17. The blanks can then all be assembled with each such connecting portion in alignment and then the plurality of tabs 45 pushed outwardly from one side so that all of them project beyond the other side of the 15 top one. This automatically prevents the tees from becoming disengaged from each other until needed, at which time the golfer need only conveniently grasp the topmost tab which is in staggered formation with respect to the others, and 20 hence is easily grasped, and lift the tee away from the pack and sever the center hold tab by a slight sideways yank.

These tabs can, of course, be used as advertising space. It is not even necessary to remove 25 them from their tees when forming and using the latter, as they can be so arranged as not to be in the way, and in fact they may even serve to help support the ball.

The score lines along which the tee is folded 30 may be applied thereto all on one surface, or all on both surfaces, or the four diagonals on one surface and the four side radii scores on the other surface. In the latter case the score lines may also be used to indicate, as by adjoining indicia 35 or reference to the directions, where to grasp the tee to form either a low tee or a high tee.

The tees may be blanked and scored in one 40 operation, and of course the scores may be made either all on one or both sides or partly on one side and partly on the other, still in the one operation. Also the forming and scoring die may be of multiple character, such that a considerable quantity of individual tees may be formed in one 45 operation of the press. Likewise these several essential operations in the making of the tee may be in conjunction with printing operations, in case the tees contain an advertisement or other indicia, or the book covers or score cards, etc., to which the tees are removably attached may 50 likewise be printed in the same manufacturing operation, or at least in conjunction therewith, so as to reduce labor expenses to the minimum.

It will, of course, also be seen that the tees 55 may be assembled in book form, one to a page, or more than one, by being formed in a continuous strip in which opposite sides are almost wholly severed while yet being slightly held to adjacent tees in the same strip, and then folded into a pack in accordion-pleated fashion beneath 60 the covers of the book. Or where the center portion is only partially severed, as in Fig. 17, the tabs so formed may then serve to prevent the tees so folded like an accordion from coming apart until needed one at a time.

There are many other combined uses for this 65 golf tee besides those suggested. For instance, as an inexpensive advertisement, a few of the tees may be formed on a large-sized business card, and the cards distributed to golfers by the advertiser. 70 Also the tees may similarly be combined with Christmas cards or other greeting cards, to make inexpensive holiday and birthday gifts; also as favors or prizes to commemorate tournaments, parties, or games.

Where the dimensions of the tee are made such that, for instance, the two rearward corners thereof are visible to the golfer because they extend beyond the curve of the ball as viewed by him or her, this feature may be used as an aid in directing the drive. Under present conditions of play, with a spherical ball, the direction in which the golfer desires to drive it must be determined by him by the position of his feet or stance, as he has no other relative indication of the desired line or direction of flight desired. With this tee, however, where for instance it can be set up so that its two rear corners are in a line at right angles to the desired flight direction, this can be determined in advance when the ball is being teed on this invention, and thereafter during the drive the golfer can gauge or interpolate the flight line as being at right angles to the imaginary line extending across the tee corners. Thus, the tee in this form can be used as a great scientific aid in helping the golfer fix his direction of drive.

Or, where the driving position of the golfer is such that he sees the two nearest corners of the tee, the line between these may be positioned in the same direction as the desired flight of the ball.

It is to be understood that the present disclosure is for the purpose of illustration only, and that the invention is not limited thereto. To those skilled in the art, many modifications of the invention will be readily apparent, and it will also be obvious to such skilled persons that parts of the device and method may be used without other parts thereof, many such combinations readily suggesting themselves. Therefore, it

should be, and is to be distinctly understood that for a definition of the limitations of the invention, reference must be had to the appended claims.

Having now described the invention, what is claimed as new and for which Letters Patent of the United States is desired is:

1. A golf tee of foldable material cut from a single flat piece to an approximately square outline and scored along its diagonals and also along intermediate radial lines and adapted to thereafter be folded along said scores to elevate its center portion. 10

2. A golf tee having a center opening, a surrounding edge approximately square in shape, 15 diagonal scores, and radial scores equi-spaced therefrom, said scores all extending substantially to said opening, and said opening being such that the points of intersection between its edge or edges and the diagonal or radial scores are equi-distant from its center. 20

3. A high-and-low golf tee, comprising a piece of approximately square foldable relatively-rigid material, diagonal and intermediate radial scores therein, and a centrally-disposed cut-away portion, all so arranged that a low tee is formed by convexing the diagonals and concaving the intermediate radial scores, and a high tee when the operation is reversed. 25

4. A golf tee made of flat foldable material and having four flat-notched or concave sides surrounding a center opening, there being one folding score connecting each corner and also each side with said center opening. 30

RAY BELMONT WHITMAN. 35
